DESIGN FOR A COAT

Harry Zuckerman, New York, N. Y.

Application December 21, 1939, Serial No. 89,056

Term of patent 3½ years

To all whom it may concern:

Be it known that I, Harry Zuckerman, a citizen of the United States of America, residing in the city of New York, county of New York, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The scarf is an integral part of the design.

The characteristic feature of my design resides in the combination on the specific coat disclosed of the trimming arranged on the sleeves and front blouse portion as shown.

I claim:

The ornamental design for a coat, substantially as shown and described.

HARRY ZUCKERMAN.
